UNITED STATES PATENT OFFICE.

EARL B. INMAN, OF PORTLAND, OREGON.

WOOD-SPLITTING MACHINE.

1,310,660.

Specification of Letters Patent. Patented July 22, 1919.

Application filed June 26, 1918. Serial No. 241,922.

To all whom it may concern:

Be it known that I, EARL B. INMAN, a citizen of the United States, residing at Portland, in the county of Multnomah and State 5 of Oregon, have invented a new and useful Wood-Splitting Machine, of which the following is a specification.

My invention relates to improvements in wood-splitting machines in which a vertical 10 riving knife is pressed into a horizontal log by means of a three-drum engine and wire cables; and the objects of my improvement are first, to eliminate the wedging and mauling of the logs by hand; second, to split logs 15 of any reasonable length and thickness especially, however, cord wood and spruce for aeroplanes; third, to produce a machine which, for the most part, can be readily constructed with the material available in any 20 logging camp.

I attain these objects by the mechanism illustrated in the accompanying drawings in which:

Figure I is a plan view of the entire machine; Fig. II, a side elevation; Fig. III, a vertical section along the line *a—a* in Fig. I; Fig. IV, a vertical section along the line *b—b* in Fig. III; Figs. V and VI are a detailed back and side view respectively of the 30 upper half of the riving knife, the lower half being symmetrical; Fig. VII is a section through the knife as indicated by the line *c—c* in Fig. VI.

Similar numerals refer to similar parts 35 throughout the several views.

The frame of my machine comprises skids 1, held together by cross beams 2 and also by a platform which, however, may be designated by the three numerals 3^a, 3^b and 3^c 40 as each of these parts serves its special purpose. 3^a is reserved for the operator, 3^b for riving knife and log and 3^c for the drums. The division line is set by the vertical side posts 4 and 5 on top of the platform. 45 Cross beam 6 rests on top of the two posts 4, and cross beam 7 on the two posts 5. Iron rods 8, so-called hog irons, are anchored in the skids and hold the posts securely in an upright position.

50 At the center line of the machine, firmly attached to the cross beams 6 and 7, is the beam 9 which serves as a guide for the upper part of the riving knife 10. The lower part of the knife is guided and also supported by the beam 11, latter being attached to the under side of the platform 3^a and 3^c.

An ordinary three-drum donkey engine 12 is placed on the platform 3^c and has its steam inlet 13 connected with a suitable steam generator. From the crank shaft 14 power is transmitted by means of gears 15 to the three drums 16, 17 and 18 and, by means of gears 19 (Fig. IV), to the shaft 20. This shaft has keyed to its ends, on the outside of the skids, the friction wheels 21. 60

A wire cable from the drum 16 leads over the sheave 22 and around the sheave 23 to the rear end 24 of beam 9 where it is attached in a suitable manner. The wire cable from drum 17 leads underneath sheave 25 and around sheave 26 to the rear end 27 of beam 11 where it also is fastened. The two last-named drums serve to pull the riving knife 10 into the log. To return the knife to its starting position a cable 28 is attached 70 to the back of the knife 10 and leads over the sheaves 29 and 30 to the drum 18. The sheaves 29 and 30 are placed slantingly so that the cable 28 may clear the obstacles underneath the platform. 80

As apparent from Figs. V, VI and VII the knife edge 10 proper is reinforced by being bolted at 31 to an I beam, and to the latter are riveted the plates 32 which, in conjunction with beams 9 and 11, guide the 85 knife and also serve as bearings for the sheaves 23 and 26 respectively.

An appropriate number of carrier chains 33 (in the drawings only two are shown on each side) travel across the platform 3^b and 90 around the rollers 34 to be driven by sprocket wheels 35. The shafts 36, on which the sprocket wheels are secured, extend past the friction wheels 21 and are provided with friction wheels 37, latter being arranged 95 slantingly so that when one of them is pressed against the wheel 21 their carrier chains will travel in one direction while an operation of the other friction wheel will produce a motion of the chains in an opposite direction. 100

In this invention no claim is made to the handling gear, therefore, latter, as well as the usual accessories to the drums, such as brakes, clutches and ratchets are, for the sake of greater clearness, omitted. Suffice 105 it to say that the operator takes his stand on the platform 3^a with the handling gear conveniently arranged before him. The log, previously sawed to proper length, is placed on to the carrier chains 33 on platform 3^b; by manipulation of the proper friction wheel 37 the log is carried in front of 110

the riving knife, to about the position indicated by the dotted circle 38 in Fig. IV. The operator makes sure that drum 18 is free to play out its cable 28 and then, by winding 5 the cables on the drums 16 and 17, the knife 10 will press against the end of the log and, if necessary push it along until the other end of the log rests firmly at the bulkhead 39 between the posts 6. From now on the knife 10 will enter the log until latter is split open and half a log deposited on the carrier chains on each side of the knife, either to be carried back before the knife, or to be thrown over the edge of the platform. 15 If the operator desires, he may advance the lower part of the knife and then follow in see-saw fashion with the upper part which will increase the splitting power materially. On the other hand, if speed is more 20 important than power, the cables may be released from the points 24 and 27 and attached directly to the sheaves 23 and 26 on the knife.

Having described my invention, it will 25 be seen that my objects have been accomplished; and though I have shown the preferred form of my machine, I reserve to myself the right to make minor changes of construction so long as I do not depart from 30 the spirit of my invention.

Especially do I wish it to be understood, that a steam-engine is not the only power generator to which I restrict myself, but that any power—gas engine, electric, or 35 otherwise—may be used, provided it is capable of driving three individual drums and a separate friction shaft.

I claim:

1. In a wood-splitting machine, the combination of a horizontal, elevated platform, 40 a longitudinal slot in the center section, a vertical knife reciprocating within the slot, a source of power controlling means for said source of power, cable drums for advancing each end of the knife independently, and a separate cable drum for withdrawing said knife.

2. In a wood-splitting machine, the combination of an elevated platform, cable drums at one end, a vertical knife extending through the platform, cables between said cable drums and each end of the knife for advancing the knife, a cable between said cable drums and the center of the knife for withdrawing the knife, sheaves disposed to 50 guide the cables, and a common source of power acting on the cable drums to advance each end of said knife independently. 55

3. In a wood-splitting machine, the combination with a vertical knife, a bulkhead, 60 means for reciprocating the knife, carrier chains at both sides of the knife, a common source of power for reciprocating the knife and operating the carrier chains, and gearing for transmitting such power to the carrier chains, to selectively drive either or both of them in the same or opposite direction. 65

4. In a wood-splitting machine, the combination of a vertical knife, a bulkhead, 70 carrier chains at both sides of the knife mounted to carry a log to or from the knife, shafts to support and drive said carrier chains, and driving gear engageable with said shafts, to drive either chain in either 75 direction.

5. In a wood-splitting machine, a riving knife, knife guiding flanges at both ends of said knife, an eye at the back of the knife, 80 sheaves between the flanges, a cable attached to the eye, cables having one end attached to a fixed point, passing around such sheaves and being attached to means for drawing such cables. 85

6. In a wood-splitting machine, a riving knife, a reinforcing bar at the back of the knife, a ring at the back of the reinforcing bar, guiding flanges at each end of said bar, 90 sheaves between said flanges, a cable attached to the ring, cables having one end attached to a fixed point and passing around such sheaves, means for guiding and drawing the free ends of said cables. 95

EARL B. INMAN.
